UNITED STATES PATENT OFFICE.

EMANUEL FISHER, OF PROVIDENCE, RHODE ISLAND, ASSIGNOR OF ONE-HALF TO
FREDERICK S. PECK, OF BARRINGTON, RHODE ISLAND.

VALVE.

1,113,976.

Specification of Letters Patent.

Patented Oct. 20, 1914.

Application filed October 21, 1912. Serial No. 726,861.

To all whom it may concern:

Be it known that I, EMANUEL FISHER, a citizen of the United States, residing at Providence, in the county of Providence and State of Rhode Island, have invented certain new and useful Improvements in Valves, of which the following is a specification.

My invention relates to rotary valves adapted for use with steam, gas, air, fluids or liquids.

The essential objects of my invention are to provide a compound opening on one port; to assure an inside lead and an increase of pressure when the valve is turned 180° from its closed position so as to insure a wash on both sides of the valve whereby all scale and accumulations will be initially removed from behind the valve; to insure the passage of a greater volume of water and a greater opening area in a given time and by a smaller movement.

Further objects are certainty of operation, simplicity and inexpensiveness of construction.

The invention accordingly consists in the features of construction, combinations of elements, and arrangement of parts which will be exemplified in the construction hereinafter set forth; and the scope of the application of which will be indicated in the appended claims.

In the accompanying drawings, which form a part of this specification,—Figure 1 is a central vertical longitudinal section of my valve, Figs. 2, 3, 4 and 5, sections of the same on line $x-x$ of Fig. 1 showing the valve in closed, partially open, more fully open, and open positions, respectively; 40 a modified form of valve being shown in Fig. 5, and Fig. 6, a section taken on line $y-y$ of Fig. 5.

Like reference characters indicate like parts throughout the views.

45 In its present and preferred embodiment my valve comprises the valve casing A, and threaded pipe openings B and C. An end plate D, attached to the casing by screws d , is provided with an opening d' through which passes the valve spindle E, extending also through a stuffing box arrangement F. A handle H is fixed to the end of the valve stem. The interior of the wall of the casing is cylindrical, but the intermediate portions 50 of its sides are recessed leaving depressions

or clearances j at both sides of a resultant relatively raised valve seat J, and intermediate annular portions j' against which the rings N bear. The valve seat J extends longitudinally of the casing and is provided with a serrated opening or port K comprising a series of connected V-shaped openings k arranged longitudinally of the valve seat.

The valve member comprises a longitudinal web M having a substantially cylindrical bearing face, also cylindrical bearing extensions or rings N integral with the ends of the web, and preferably but not essentially split as at n . The curved bearing face of the web or bar M is cut away lengthwise of the web, either in the form of a concavity, as at P in Fig. 4; or in a plane, as at P' in Fig. 5; forming two resultant parallel interspaced working faces, p , transversely curved in the same plane and conforming to the curvature of the seat J. The width of each face p is substantially the same or less than the width of the individual portions of the valve seat J at either side of the port K; and when the valve is closed its faces p are 80 against those portions of the valve seat, as shown in Fig. 2.

The spindle E is integral with or fixed to one of the two end plates or lugs O upon the web M within the planes of the rings N. The spindle may be connected with the valve in any other known manner.

It will be observed by reference to Fig. 2 that when the valve M has been turned in the direction of the arrow to such a position that one of the surfaces p is about to disclose the pointed portions of the opening K, the other surface p of the valve has left the seat J and overhangs the clearance j so that the liquid or fluid passing through 95 the opening B moves intermediate the rings N and under the last mentioned surface p and through the port K, thus initially removing all scale and accumulations from behind the valve prior to the full opening of 100 the latter by virtue of this inside lead.

In Fig. 4 the valve M is shown moved farther in the direction of the arrow disclosing a greater area of the port K and permitting the fluid or liquid to pass from the 105 opening B simultaneously around both sides of the valve affording a compound opening upon a single port.

In Fig. 5 the valve M is shown advanced to such a degree as to entirely disclose the 110

port K and the coincidence of the surface *p* with the left hand portion of the valve seat *J* cuts off from the port in advance the liquid to the latter through the clearance *j*.

5. When the valve is turned to a position directly opposite its full closed position, which latter is shown in Fig. 2, the valve being moved 180°, the water flowing in both directions through the clearances *j* upon opposite sides of the valve will be under increased pressure and will serve to more effectively and efficiently remove all mud or sediment not only from the working faces *p* of the valve but also from the walls of the clearances and of the valve seat *J*.

15. Not only is a wash upon both sides of the valve obtained by my structure, but the volume of liquid or fluid is controlled by a minimum of valve travel and expenditure of time. The serrated character of the port opening K is found to be particularly advantageous in the operation of the structure, but it will be understood that satisfactory results are secured with valve openings of unserrated form. The rotary character 20 of my valve and its described construction makes its operation in a direction opposite to that indicated by the arrows equally feasible.

25. What I claim is:—

30. 1. In a valve, a casing provided with a port and a valve seat surrounding the same with a clearance upon each side of said seat, and a valve member rotatably mounted and comprising a transversely curved web provided with working faces adapted to co-operate with said port and seat and to permit of a double opening, whereby the fluid may flow through at either side of the valve 35 member and permitting the fluid to flow across the seat upon opposite sides of said port when the valve is open.

35. 2. In a valve, a casing provided with a port having a series of connected V-shaped openings and a valve member rotatably mounted and having a transversely curved web for co-operation with said seat and to straddle said port when the valve is closed, there being a clearance upon each side of 40 said seat whereby fluid is permitted to flow across the seat upon both sides of the port when the valve is open.

45. 3. In a valve, a cylindrical casing provided with recessed portions providing clearances and a valve seat intermediate the same and provided with a port, and a valve rotatably mounted in the casing and comprising a web provided with bearing faces inter-spaced from each other substantially the 50 width of the port and adapted to slide upon said seat and permit of the flow of fluid on both sides of the valve and to permit fluid to flow across the seat upon both sides of the port when the valve is open.

55. 4. In a valve, a cylindrical casing pro-

vided with recessed portions providing clearances and a valve seat intermediate the same and provided with a port comprising a series of connected V-shaped openings, and a valve rotatably mounted in said casing 70 and comprising a web provided with two parallel curved bearing faces interspaced from each other substantially the width of the port and adapted to slide upon said seat to permit fluid to flow through the inlet 75 opening of the casing simultaneously around both sides of the valve.

5. In a valve, a cylindrical casing provided with recessed portions providing clearances and a valve seat intermediate the 80 same and provided with a port comprising a plurality of V-shaped openings, a valve comprising a web provided with parallel interspaced working faces adapted to engage the seat and spaced apart substantially the width 85 of the port and constructed to permit the flow of fluid from the opening in the casing substantially around both sides of the valve, extension rings upon the ends of the valve, and a valve stem for said valve.

6. A valve comprising a chamber, a valve member rotatable in the chamber, an inlet port to the chamber and an outlet port leading therefrom, seats facing toward the inlet, faces spaced apart on said valve adapted to 95 co-operate with said seats to control the outlet, the chamber being recessed between said seats and said inlet port to allow fluid to flow across both seats when the valve is open.

100. 7. A valve comprising a chamber, an inlet thereto, a rotatable valve member within the chamber with its axis parallel with the said chamber, an outlet beyond the valve, a valve seat surrounding the outlet and a recess within the valve chamber and extending to the valve seat, whereby fluid is permitted to flow across both seats when the valve is open.

105. 8. A valve comprising a chamber, a valve member rotatable in the chamber, an inlet port to the chamber and an outlet port leading therefrom, seats facing toward the inlet, faces spaced apart on said valve adapted to co-operate with said seats, to control the outlet, the chamber being recessed between said seats and said inlet port to allow fluid to flow across both seats when the valve is open, the width of each of the said faces being substantially the same as the width 110 of the individual portions of the valve seat at either side of its port.

115. 9. In a valve, a valve casing having a seat and a port therethrough and a recess within said casing extending to the valve seat upon each side of the port and a rotary valve member therein having a portion intermediate its ends acting in conjunction with the casing to permit of the flow of liquid 120 under increased pressure upon opposite sides 125 130.

thereof when the valve member is diametrically opposite its closed position.

10. In a valve, a valve casing having a relatively raised curved seat facing axially of the casing with clearance except at said seat, and a valve member rotatably mounted in said casing and acting in conjunction with said clearance to permit of the flow

of liquid around both sides of the valve and seat when the valve is moved from its seat. 10

In testimony whereof I have affixed my signature in presence of two witnesses.

EMANUEL FISHER.
